(57) **CLAIM**

The ornamental design for a fluid product dispenser, as shown and described.

DESCRIPTION

FIG. 1 is side left view of a fluid product dispenser;

FIG. 2 is a side right view thereof;

FIG. 3 is a front view thereof;

FIG. 4 is a rear view thereof; and,

FIG. 5 is a top view thereof.

The broken lines are included for the purpose of illustrating a portion of the fluid product dispenser that forms no part of the claimed design.

1 Claim, 5 Drawing Sheets

FIG. 1

FIG. 2

FIG. 3

FIG. 4

FIG. 5
